C. H. HUGHES,

OUTLET VALVE FOR GASOLENE DISPENSING APPARATUS OF FILLING STATIONS.
APPLICATION FILED JUNE 25, 1920.

1,377,835.

Patented May 10, 1921.

UNITED STATES PATENT OFFICE.

CHARLES H. HUGHES, OF DENVER, COLORADO, ASSIGNOR OF ONE-HALF TO FRED C. CRAMER, OF DENVER, COLORADO.

OUTLET-VALVE FOR GASOLENE-DISPENSING APPARATUS OF FILLING-STATIONS.

1,377,835.

Specification of Letters Patent. Patented May 10, 1921.

Application filed June 25, 1920. Serial No. 391,762.

To all whom it may concern:

Be it known that I, CHARLES H. HUGHES, a citizen of the United States of America, residing at the city and county of Denver and 5 State of Colorado, have invented a new and useful Outlet-Valve for Gasolene-Dispensing Apparatus of Filling-Stations, of which the following is a specification.

This invention relates to improvements in 10 outlet valves for gasolene dispensing apparatus of filling stations. The object of the invention is to provide an outlet valve for gasolene dispensing receptacles or containers such as are employed at automobile 15 filling stations, which after being opened, is closed by gravity when released, to cut off the flow of gasolene when the desired quantity has been withdrawn. Further, to provide a graduated, gasolene dispensing receptacle 20 having an outlet pipe provided with a discharge valve which is manually opened, but closed by combined spring and gravity action, when released, to cut off the flow of gasolene when the desired quantity has been 25 withdrawn.

Further, to provide a gasolene dispensing receptacle having a valve controlled liquid outlet pipe normally in communication with an air inlet, and means operated by the opening 30 of the valve whereby air is cut off from the outlet pipe while the valve is open, but admitted to the said pipe when the valve is closed to cut off the outflow of gasolene, thereby preventing the forming of a vacuum, 35 in the usual filling hose, which is attached to the outlet pipe, whereby the same is completely drained, and subsequent dripping thus prevented.

These objects are accomplished by the apparatus 40 illustrated in the accompanying drawings, in which:

Figure 1 is a side elevation of a gasolene dispensing apparatus constructed in accordance with my invention.

Fig. 2 is a vertical sectional view of the dispensing receptacle.

Fig. 3 is a vertical sectional view of the air pipe at the upper end of the receptacle, a portion of the pipe which connects the 50 same with the outlet pipe, and the air controlling valve carried by said connecting pipe, and

Fig. 4 is a perspective view of the lower end of the connecting pipe, illustrating its arrangement as an outlet valve.

55

In apparatus of this character, in present use, the outlet pipe of the gasolene measuring receptacle, to which the usual service hose is connected, is provided with a manually-operated cock or valve, which opens or 60 closes communication between the receptacle and the service hose. When the desired quantity of gasolene is drawn from the receptacle, the valve is closed, and as the gasolene which is in the hose, flows out, a 65 partial vacuum is thereby formed in the hose, which causes the said gasolene to discharge therefrom in a slow, irregular stream, which finally becomes a mere dribble. Thus, considerable time is required to drain the 70 hose, under present conditions, and even then, the hose will drip.

The present invention eliminates these objectionable features by providing a form of outlet valve which, as it cuts off the flow of 75 gasolene from the receptacle, effects the entrance of air in the outlet pipe, which prevents the forming of a vacuum in the service pipe, thus insuring a quick and thorough draining of the same.

80

Referring to the accompanying drawings:

The numeral 1, indicates a hollow, transparent, glass cylinder which is open at both ends, and which may be of any desired dimensions, but which, in practice, is approximately twelve inches in diameter, by about thirty-four inches in length. The cylinder is closed at its ends by metal heads 2 and 3, which are clamped upon the said ends by 85 headed rods 4, which extend through flange portions 5, of said heads, and receive clamping nuts 6. The flange portions of the heads are provided with circular grooves 7, in which are placed suitable flexible gaskets 8, 90 against which the ends of the cylinder bear, and which prevent leakage, as will be understood.

Each head comprises the flange 5, and an outwardly projecting hub or ring 9, 100 and upon these hubs or rings are bolted circular plates or caps 10 and 11, respectively, which close the heads and likewise, the ends of the cylinder.

The bottom cap 11, has a central aperture in which is rigidly secured, by brazing or otherwise, a short pipe 12, which extends about equal distances beyond each side of the plate, its upper end being on a level with the adjacent flange 5, of the head. Upon the end of the pipe 12, is secured a reducer 13, to which is suitably connected one end of a service or filling hose 14, through which gasoline from the measuring receptacle or container is supplied to the tank of an automobile or to any other receptacle.

On opposite sides of the central aperture in the bottom cap 11, are threaded apertures 15 and 16, in which are screwed the lower end portions of pipes 17 and 18, respectively, which extend to within a short distance of the top of the glass cylinder 1. The threaded lower end of the pipe 18, extends slightly below the cap 11, and is connected by an elbow 19, with a pipe 20, which connects with a pump, of any style in common use, for pumping the gasoline from the general supply tank to the container 1, the said pump being omitted as it forms no part of the present invention.

The pipe 17, is the overflow pipe and its upper end, therefore, defines the highest level of the gasoline in the container 1. This end of the pipe is provided with a hood 21, the purpose of which will later appear. The lower end of the pipe 17, is connected by an elbow 22, with a pipe 23, which connects with the general supply tank, and thus conveys the overflow from the container 1, to the general supply tank.

The gasoline, entering the container through the supply pipe 18, is under sufficient pressure to be thrown against the upper cap 10, and thereby deflected in all directions, and but for the hood 21, a portion of the gasoline would enter the pipe 17, and flow back to the tank, but the hood extends over the top of the pipe and prevents gasoline from entering the same, until the gasoline fills the container to level of the top of the said pipe, which defines the greatest depth of gasoline in the container, as before stated.

The upper end of the inlet pipe 18, is on a slightly higher level than the upper end of the overflow pipe, otherwise the overflow pipe could not carry out its function.

The upper cap 10, has a threaded aperture in which is screwed a short pipe 24, which acts as a vent for the container, and a short pipe 25, is rigidly secured in an aperture in the center of the said cap, in axial line with the pipe 12, in the lower cap 11. The pipe 25, extends a short distance above the cap 10, and also below the same, its lower end terminating slightly below the level of the upper end of the pipe 17, and the upper end of the pipe 25 is closed by a screw cap 26,

having a central aperture 27. A pipe 28, connects the pipes 25 and 12, the upper end portion of the pipe 28, fitting slidably in the pipe 25, while its lower end portion fits slidably in the pipe 12, and its downward movement is limited by a stop collar 29, which is rigidly secured upon the said pipe, a short distance above its lower end, and a flexible washer 30, which fits tightly on the pipe and against the lower end of the stop 29. This washer normally rests upon the upper end of the pipe 12, and securely seals the upper end of the said pipe when in this position.

The lower end portion of the pipe 28, which projects into the pipe 12, is provided with three or more holes 31, and this end of the pipe with its holes 31, constitutes the improved outlet valve for the container, taken in connection with the upper end of the pipe 12.

As shown in Fig. 2, the valve is in position to close the outlet pipe 12; but when the pipe 28, is raised in a manner to be presently described, to bring the holes 31, above the upper end of the pipe 12, the gasoline in the container flows through the holes 31, into the pipe 12, and out through the service hose 14.

The upper end of the pipe 28, extends a short distance into the pipe 25, terminating above the level of the upper end of the overflow pipe, and an expansion coil spring 32, is interposed between the upper end of the said pipe 28, and the screw cap 26, and acts to normally exert a downward pressure on the pipe and securely seat the washer 30, upon the upper end of the pipe 12.

A pin 33, extends through the upper end portion of the pipe 28, and this pin extends loosely through the forked lower end of a stem 34, which extends up through the spring 32, to within a sort distance of the cap 26; and a rod 35, is screwed into the upper end of this stem, and extends out through the hole in the cap 26. A metal washer 36, rests upon the upper end of the stem, and supports a flexible washer 37, which acts as a valve to close the hole 27, in the cap 26, when the pipe 28, is raised, for a purpose to be presently explained.

In practice, the upper head 2, of the container is secured, in any suitable manner to a support 38, usually one of the roof beams of the filling station, the lower head of the container being far enough above the ground to be out of the way of automobiles. As the container is transparent, the depth of the gasoline therein can be ascertained at a glance, and the outer surface of the container is graduated to indicate gallons and fractions thereof up to fifteen gallons.

The upper end of the rod 35, is pivotally connected to one end of a lever 39, which is pivotally supported by a suitable bracket 130

40, secured to the support 38. To the opposite end of this lever is connected the upper end of a rod 41, the lower end of which is provided with a stirrup-like handle 42, 5 which is in easy reach of an attendant.

In practice, gasolene is pumped into the container in the manner before described, until it reaches the level of the upper end of the overflow pipe 17, which is indicated 10 by zero on the graduated scale. When any quantity, from one to fifteen gallons is required, the handle 42, is grasped and the rod 41, is drawn upon, by which the lever 39, is rocked, and the pipe 28, thereby raised, until the washer 37, on the stem 34, engages the 15 cap 26, and prevents further upward movement of the pipe. When the washer 37, engages the cap, it closes the aperture 27, and thus prevents the entrance of air into the 20 pipe 28.

When the pipe 28, reaches the limit of its upward movement, the holes 31, in its lower end are above the upper end of the outlet pipe 12, and the gasolene flows through the 25 holes 31, to the pipe 12, thence through the service hose 14, to the automobile tank, or other receptacle.

When the gasolene level drops to the line indicating the number of gallons required, 30 the handle 42, is released and the pipe 28, drops, under the combined action of gravity and the spring 32, until the washer 30, engages the end of the outlet pipe 12, and prevents further downward movement of the 35 pipe, and as the end of the pipe 28, having the holes 31, is now entirely within the pipe 12, the outflow of gasolene is cut off. A vacuum in the container is prevented by the vent 24, in the upper cap 10, which permits 40 the gasolene to flow out under normal atmospheric pressure.

While the outlet valve is held open, to permit the discharge of gasolene from the container, the air hole 27, in the cap 26, is closed 45 by the valve or washer 37, and air is thus cut off from the pipe 28, and the out-flowing gasolene, after entering the outlet pipe, is free from air pressure in the said pipe 28. The reason for cutting off air from the pipe 50 28, is, that experience has demonstrated that when air is admitted above the gasolene flowing out through the hose, in addition to the atmospheric pressure in the container, the gasolene discharges from the hose in an irregular stream; but when the air is cut off from the pipe 28, and the gasolene is subjected only to the atmospheric pressure in the tank, the flow through the hose is steady and unbroken.

60 The apparatus above set forth while primarily designed for the measuring and dispensing of gasolene, may also be used for free flowing oils and other liquids, and the construction of the apparatus permits the 65 removal of each cap, and parts supported

thereby, independently of the other cap, thus facilitating repairs and changes when necessary.

Having described my invention, what I claim as new and desire to secure by Letters Patent, is:

1. In an apparatus of the character described, the combination with a closed liquid-measuring container having a liquid outlet pipe in its lower end and an air inlet pipe 75 at its upper end, of a gravity tube, the end portions of which are slidably mounted in said pipes, the portion of said tube in said outlet pipe having outlet openings, means for lifting said tube to expose the outlet 80 openings therein, means for closing the air inlet, simultaneously with the opening of the liquid outlet, and a vent in the container.

2. In an apparatus of the character described, the combination with an inclosed liquid-measuring container having a liquid outlet pipe in its lower end, and an air inlet pipe in its upper end, of a gravity tube, the end portions of which are slidably mounted in said pipes, the portions of said tube within said outlet pipe having outlet 90 openings; a valve member on the upper end of said tube, a lever for raising said tube to expose said outlet holes, and thereby permit the liquid to flow into the outlet pipe, said valve member acting as the same time to close said air inlet, and a vent in said 95 container.

3. In a device of the character described, 100 the combination with a closed liquid-measuring container having a liquid outlet and an air inlet communicating with the outlet, a gravity device arranged to normally close the outlet and open the inlet, means for raising the gravity device whereby the inlet is 105 closed and the outlet opened, and a vent in said container.

4. In a device of the character described, 110 the combination with a closed liquid-measuring container having a liquid outlet and an air inlet, of a tubular gravity device connecting said inlet and outlet and arranged to normally close said outlet and open said inlet, a lever for raising said tubular gravity 115 device whereby said outlet is opened and the inlet closed, and a vent in said container.

5. In a device of the character described, 120 the combination with an inclosed liquid-measuring container having a liquid outlet and an air inlet, of a pipe the end portions of which are slidably mounted in said inlet and outlet, said pipe being arranged to normally close said outlet and open said inlet, a lever for raising said pipe whereby 125 the outlet is opened and the inlet closed, and a vent in said container.

6. In a device of the character described, 130 the combination with a liquid-measuring container having a liquid outlet pipe and an

- air inlet pipe in axial line, a connecting pipe slidably mounted at its end in said outlet and inlet pipes and adapted normally to close communication between the container 5 and the outlet pipe and connect the air inlet and liquid outlet pipes, a lever for raising said pipe, whereby the container and outlet pipe communicate, and the air inlet is closed, and a vent in the container.
- 10 7. In a device of the character described, the combination with an inclosed liquid-measuring container having a liquid outlet pipe and an air inlet pipe in axial line, of a connecting pipe, the ends of which are slidably mounted in said pipes, the portion of the connecting pipe within the outlet pipe having outlet holes, a valve member on the upper end of the connecting pipe, said pipe normally acting to close communication between the container and outlet pipe, and connect the air inlet and liquid outlet pipes; a lever for raising the connecting pipe whereby its outlet holes are exposed to permit communication between the container 20 and outlet pipe, while at the same time the said valve member closes the air inlet, and a vent in the container.
8. In a device of the character described, the combination with an inclosed liquid-measuring container having a liquid outlet pipe and an air inlet pipe in axial line, a combined gravity and spring actuated connecting pipe slidably mounted at its ends in the said outlet and inlet pipes, the part of 30 said connecting pipe inclosed by the outlet pipe having outlet holes, a valve member supported on the upper end of the connecting pipe, said pipe normally acting to close communication between the container and outlet pipe and open communication between the outlet pipe and the air inlet pipe, a lever for raising said 35 connecting pipe, whereby the outlet from the container is opened and the air inlet closed, a stop on the connecting pipe and a gasket thereagainst, which normally rests on the top of the outlet pipe, and a vent in the container.
- 40 9. The combination with a liquid-measuring container having removable end caps, of an air inlet pipe in the upper cap and a liquid outlet pipe in the lower cap, said 45 pipes being in axial line, a screw cap on the air inlet pipe having an air hole, a connecting pipe slidably mounted at its ends in said pipes, a stop sleeve on the connecting 50 pipe and a gasket thereagainst, which normally rests upon the end of the outlet pipe, the portion of the connecting pipe inclosed by the outlet pipe having outlet openings, a stem pivotally connected to the upper end of the connecting pipe, a rod connected to said stem and extending out through said air hole, a gasket on the upper end of said stem, and a coil spring interposed between the end of said connecting pipe and said screw cap, said connecting pipe normally closing communication between the container and outlet pipe and opening communication between the air inlet and the liquid outlet pipe, a lever connected to said rod to raise said connecting pipe, whereby the outlet holes in said pipe are exposed to open communication between the container and the outlet pipe, and the air hole in the screw cap is closed by the gasket on said stem, and a vent in said container.
10. The combination with a liquid-measuring container having a liquid inlet pipe, an overflow pipe, and a liquid outlet pipe and an air inlet pipe in axial line, of a combined gravity and spring actuated connecting pipe, the ends of which are slidably 80 mounted in the air inlet and liquid outlet pipes, and arranged to normally close communication between the outlet pipe and the container, and connect the said outlet pipe and the air inlet pipe, a lever for raising said 85 connecting pipe, whereby the outlet from the container is opened and the air inlet closed, a stop on the connecting pipe and a gasket thereagainst, which normally is seated on the end of the outlet pipe, and a 90 vent in the container.
11. The combination with a graduated transparent container having a liquid inlet pipe, an overflow pipe, and an air inlet pipe and a liquid outlet pipe in axial line, of a 95 connecting pipe slidably mounted at its ends in the said air inlet and liquid outlet pipes, and adapted to normally close communication between the container and outlet pipe, and open communication between the outlet 100 pipe and the said air inlet pipe, means for raising the connecting pipe whereby the air inlet is closed and the liquid outlet opened, and a vent in the container.
- In testimony whereof I affix my signature 110 in presence of two witnesses.
